UNITED STATES PATENT OFFICE.

LYNN WALTER DANFORTH, OF TULSA, OKLAHOMA.

TIMER.

Application filed March 11, 1922. Serial No. 543,007.

To all whom it may concern:

Be it known that I, LYNN WALTER DANFORTH, a citizen of the United States, residing at Tulsa, in the county of Tulsa and 5 State of Oklahoma, have invented a new and useful Timer, of which the following is a specification.

This invention aims to provide, in a timer, novel means whereby the contact member 10 which is carried by the shaft will be held yieldingly against a disk or carrier which supports a plurality of contacts.

Another object of the invention is so to construct the timer shaft that the conductors 15 will be protected against contact with the fan or fan belt and be protected, likewise, against saturation with oil or water.

It is within the province of the disclosure 20 to improve generally and to enhance the utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:

Figure 1 shows in front elevation, a device constructed in accordance with the invention; Figure 2 is a rear elevation; Figure 3 is a fragmental longitudinal section wherein parts appear in elevation; Figure 4 is an elevation showing the carrier; Figure 5 is an elevation showing the collar and the spring 40 member which carries the contact; and Figure 6 is a section on the line 6—6 of Figure 4.

The timer forming the subject matter of this application includes a casing 1 having the usual means 2 whereby it may be moved 45 to change the timing. Suitable means (not shown) engage a depression 3 in the casing 1 to hold the casing assembled with any accessible part of the engine 4. The casing 1 has an internal recess 5 defining a shoulder 50 6. A disk or carrier 7, preferably made of insulating material, is mounted in the recess 5 and engages the shoulder. An expandible

retaining ring 8 is disposed within the casing 1 and is interposed between the disk or carrier 7 and the part 4 of the engine, to 55 hold the disk in the casing. The disk 7 carries terminals 9 having threaded stems 10 on which nuts 11 are mounted, one nut 11 serving to retain the terminal in place, and the nuts 11 on each terminal 10 cooperating to 60 retain conductors 12 which, preferably, pass through a conduit 14 mounted if desired in an insulating thimble 15 carried by the casing 1. The conductors 12, it will be noted, are so housed and protected that they will 65 not come into contact with the fan belt, nor will they be exposed to the action of oil, moisture or the like. The disk or carrier 7 has a central opening 66 and is provided with a forwardly projecting sleeve 16. 70

The shaft is indicated at 17 and projects into the opening 66 of the disk 7, and into the sleeve 16 thereof. On the shaft 17 is mounted a support 18, in the form of a collar having notches or seats 19 and 20, the 75 seat 19 receiving a key 21 or the like on the shaft 17, the collar thus being connected to the shaft to rotate therewith. The collar 18 is surrounded by a helical retraction spring 22 one end of which is provided with a finger 23 engaged in the seat 20, so that when the collar 18 rotates with the shaft 17, the spring 22 will rotate likewise. The spring 22 is supplied at its rear end with an outstanding arm 24 carrying a contact 25. 80 85 The spring 22 serves to draw the arm 24 toward the disk or carrier 7, the contact 25 bearing against the rear surface of the disk and coacting with the terminals 9.

What is claimed is:

1. In a device of the class described, a casing having a recess defining an internal shoulder in the casing, a disk in the recess and abutting against the shoulder, an expandible ring in the recess and engaging the disk, terminals on the disk, a shaft supported for rotation, a spring about the shaft, means for securing one end of the spring to the shaft, and a contact carried by the other end of the spring, the spring being retractile to draw the contact against the disk and the terminals, the disk having an opening for the reception of the spring. 95 100
2. In a device of the class described, a

casing, a disk like carrier engaged peripherally with the casing and having an opening, terminals mounted on the carrier, a shaft extended into the opening, a retractile helical spring extended into the opening and disposed in cylindrical form about the shaft, means for securing one end of the cylindrical portion of the spring to the shaft, the other end of the cylindrical portion of the

spring having an outstanding arm, and a contact mounted on the arm, the spring serving to maintain the contact in engagement with the carrier, for cooperation with the terminals.

In testimony that I claim the foregoing as my own, I have hereto affixed my signature.

LYNN WALTER DANFORTH.
